UNITED STATES PATENT OFFICE

ROBERT I. LEWIS, OF WILMINGTON, CALIFORNIA, ASSIGNOR TO SHELL DEVELOPMENT COMPANY, OF SAN FRANCISCO, CALIFORNIA, A CORPORATION OF DELAWARE

REFINING HYDROCARBON OIL

No Drawing.

Application filed September 26, 1928. Serial No. 308,583.

This invention relates to the refining of hydrocarbon oils, especially petroleum oils, with sulfuric acid, and more particularly to such refining at temperatures below normal.

5 It is an object of this invention to reduce the losses of material, desirable as motor fuel, in the refining of hydrocarbon oils, especially in the refining with sulfuric acid, and more particularly in the refining with sulfuric acid at temperatures below atmospheric.

Further objects of this invention will appear from the following description in which I have set forth the preferred method of my invention. It is to be understood that the 15 appended claims are to be accorded the scope and range of equivalents consistent with the prior art.

Principally my invention consists in subjecting the hydrocarbon oils after a refining 20 treatment with sulfuric acid at low temperature, to an additional treatment with a relatively small amount of acid at normal temperature.

In the following I will describe my invention particularly in relation to the refining of pressure distillate, the distillate resulting from cracking processes, which contains the gasoline fractions formed by the conversion of heavier oils during the cracking. It is to 30 be understood that I do not limit my invention to the treatment of pressure distillate, as treatments according to the principle of my invention can advantageously be applied to many other hydrocarbon oils.

35 The pressure distillate from many cracking stocks is high in sulfur bearing compounds, which are very detrimental in a motor fuel, and have to be removed from the gasoline fractions, before these are marketable.

40 According to the specifications of the United States Government for motor gasoline the sulfur content may not be more than 0.1 of 1%. The removal of sulfur compounds is frequently done by a treatment with strong sulfuric acid of 55 Bé. or stronger, followed by redistilling. The sulfur compounds are partially removed in the heavy sludge formed, while a portion remains in the acid treated 45 distillate. The compounds in this last mentioned portion have been polymerized to such

an extent that the increase in their boiling points causes them to remain in the rerun bottoms on the subsequent redistilling, and not pass over with the gasoline vapors. This treatment with strong sulfuric acid over 55 Bé. at normal temperature, around 60° F. however, causes heavy losses of desirable gasoline hydrocarbons, present in the pressure distillate. The reaction between the acid and the hydrocarbons is not fully understood, but it is assumed that the losses are caused partly by evaporation due to the heat generated by the reaction of the acid on the oil, partly by dissolution in the sludge formed, partly by polymerization into tarlike heavy bodies, settling out as sludge, and partly by polymerization into heavier polymerized hydrocarbons. An increase in specific gravity and rise of boiling point, takes place whereby the gasoline hydrocarbons become less volatile to such an extent that they can not be used as gasoline, and are lost as such.

To reduce the losses in gasoline material caused by this treatment it has recently been proposed to treat the pressure distillate with 75 strong sulfuric acid at temperatures below normal, approximately at 20-10° F. At these temperatures the action of the sulfuric acid on the oil is probably one of solution rather than of polymerization. Also the sulfur 80 compounds are apparently to a lesser extent polymerized by the acid and more dissolved. This cold treatment has many advantages as it nearly eliminates the loss by evaporation, and greatly reduces the other losses of hydrocarbons.

85 However, I have found that this cold treatment has a marked disadvantage, namely that on rerunning the cold treated pressure distillate part of the sulfur compounds do not 90 remain in the rerun bottoms, but distill over with the gasoline vapors to a greater extent than in rerunning pressure distillate which is treated with sulfuric acid at normal temperature. Although the reduction of the 95 sulfur content during the cold acid treatment is much better than during the treatment at normal temperature, the decreased further reduction during the rerunning leaves the sulfur content of the finished gasoline after 100

the rerunning nearly the same in both treatments. In my opinion the explanation of this is that in the cold treatment the remaining sulfur compounds do not undergo a raise in boiling points because of less polymerization, and partly do not lose their volatility to an extent sufficient that they will remain in the rerun bottoms and not distill over with the gasoline vapors in the rerunning.

- 10 The reduction of the sulfur content is one of the main objects of the treatment with sulfuric acid, and therefore, the fact that a larger part of the sulfur compounds remains in the gasoline on rerunning, is important 15 and impairs the advantages of the cold treatment.

I have discovered that this disadvantage can be overcome by treating the pressure distillate after the cold treatment and before rerunning with a limited amount of strong 20 sulfuric acid of 55 Bé. or stronger at normal temperature. This probably polymerizes the sulfur compounds left by the cold treatment sufficiently to cause them to remain in the rerun bottoms. The amount of acid used for 25 this additional treatment is too small to cause any material vaporization loss, and hardly any sludge is formed, as the materials which are apt to form sludge have substantially been 30 removed by the previous cold treatment. The gasoline obtained after this additional treatment and rerunning shows a very markedly lower sulfur content than the gasoline obtained by the cold treatment and rerunning 35 only. Another advantage of my invention is that the color stability of the cracked gasoline is also decidedly improved, and compares very favorably with that of straight run gasoline.

As an illustration of the operation of the 40 process, I may state, that when treating pressure distillate containing 0.7% of sulfur with about 12 lbs. per barrel of strong sulfuric acid of 66 Bé. at normal temperature the sulfur content of the gasoline recovered after 45 rerunning was 0.4%, and after the cold treatment and rerunning the sulfur content was about the same, though the losses in material were substantially reduced. When I treated 50 the pressure distillate according to my invention, using the same total amount of strong acid, 12 lbs. per barrel, but dividing this in a cold treatment at 20° F. with about 9.5 lbs. acid and a subsequent treatment at atmospheric 55 temperature around 60° F. with about 2.5 lbs. acid of the same strength the sulfur content was reduced to 0.22%. The color of the cold treated gasoline when finished was 27 and after 4 weeks of dark storage had 60 dropped to 25; that of the gasoline treated according to my invention was at first 30 and in the dark after 4 weeks dropped only to 28, a considerable improvement. These figures and conditions are not to be taken as a limitation of the scope of the invention but as an

illustration of the beneficial results of my process in a given case.

If in the application of my process it would not be desired to reduce the sulfur content further than was done before with the other 70 treatments, or in the above figures, only to 0.4%, instead of to 0.22%, then much less acid is needed in my process to obtain the same results. Treating the same pressure distillate as in the case referred to above, a reduction of the sulfur content to 0.4% was obtained with only 8 lbs. of acid, divided again in about the same proportions, $\frac{4}{5}$ at low temperature, and $\frac{1}{5}$ subsequently at atmospheric 75 temperature.

80 I claim as my invention:

1. The process of preparing a gasoline of reduced sulfur content comprising: treating pressure distillate with concentrated sulfuric acid at about 20° F., and subsequently before 85 redistilling further treating the distillate at atmospheric temperature with sulfuric acid of the same concentration and of an amount equal to about one-fourth of that used in the cold acid treatment, and redistilling the 90 treated pressure distillate.

2. The process of preparing a gasoline of reduced sulfur content by treatment with concentrated sulfuric acid comprising: treating the gasoline distillate with four-fifths of the 95 acid at a temperature of about 20° F., and subsequently before redistillation treating the distillate with the remaining acid at an atmospheric temperature of about 60° F., and redistilling.

3. The process to reduce the sulfur content and improve the color of a cracked gasoline comprising: treating the pressure distillate with about 9½ pounds per barrel of 66° Bé. sulfuric acid at a temperature of about 20° F., 105 and subsequently before redistilling treating the distillate with about 2½ pounds per barrel of 66° Bé. sulfuric acid at atmospheric temperature of around 60° F., and redistilling the treated pressure distillate.

110 In testimony whereof, I have hereunto set my hand.

R. I. LEWIS.
